ATTORNEY.

UNITED STATES PATENT OFFICE.

WILLIAM H. HEISE, OF LOS ANGELES, CALIFORNIA.

STRETCHER.

Application filed May 9, 1925. Serial No. 29,051.

This invention relates to a stretcher which is useful in undertaking establishments for transporting corpses and is useful in hospitals and the like, for carrying patients or 5 invalids.

It is an object of my invention to provide a wheeled stretcher having an adjustable back or head frame. This back is pivotally secured to the frame of the stretcher and 10 may be positioned at various inclinations so that a person thereon may be comfortable.

It is another object of my invention to provide a ratchet and release arrangement for releasably retaining the back in various 15 positions. This ratchet arrangement comprises a ratchet plate which is secured to the back and a resilient member which is carried by the frame of the stretcher and which is in removable engagement with the 20 teeth of the ratchet plate. Attached to this member is a releasing means by which the resilient member is removed from engagement with the ratchet. The back may be swung upwardly without manually removing 25 the pawl from engagement, but can be lowered only by operating the resilient retaining member to remove it from engagement with the ratchet plate.

A further object of my invention is to 30 provide a stretcher of the character mentioned having a fabric carried by the frame, which is removable. The fabric is provided with flaps which extend around the frame, which flaps are laced together on the under- 35 side. By removing the lacing the fabric may be readily removed. The back or head frame is likewise provided with a removable sack or cover. This feature is very desirable as it will be possible to readily remove the fabric and replace it by a clean 40 fabric in event the first fabric becomes soiled.

It is an additional object of my invention to provide a stretcher which may be conveniently carried. I provide a carrying frame 45 which is supported by a main frame of the stretcher at the head end thereof. This carrying frame is slidably carried and when it is desired to carry the stretcher, this 50 frame may be slid outwardly into such a position that a person may take hold of the carrying frame without any interference by the head frame of the stretcher.

It is also an object of this invention to 55 provide a stretcher of the character men-

tioned having an adjustable foot frame. This foot frame may be swung into a vertical position and serve to push and guide the stretcher. It is sometimes convenient to push the stretcher along the floor. At 60 such times, it would be desirable to swing the foot frame into vertical position.

Other objects and the salient advantages of this invention will be made manifest hereinafter.

Referring to the two sheets of drawings which are for illustrative purposes and in which I show a preferred form of my invention,

Fig. 1 is a perspective view of a stretcher 70 embodying the essential features of this invention.

Fig. 2 is an enlarged fragmentary sectional view of the head end of the stretcher shown in Fig. 1, this view being taken 75 substantially on the line 2—2 of Fig. 1.

Fig. 3 is an enlarged fragmentary sectional view of the ratchet and releasing mechanism of my invention, this view being taken substantially on the line 3—3 of Fig. 80 2.

Fig. 4 is a bottom plan view of the stretcher shown in Fig. 1.

Fig. 5 is a section on the line 5—5 of Fig. 2.

Figs. 6, 7 and 8 are fragmentary views illustrating the foot frame of my invention.

The form of my invention shown in the drawings comprises a main stretcher frame 11 which is composed of side bars 12, a 90 head bar 13 which extends between the head ends of the side bars 12, being connected thereto by corner fittings 14, and a foot bar 16 which extends between the foot ends of the side bars 12, being connected thereto by 95 corner fittings 17. Extending downwardly from the head fittings 14 and the fittings 19 which are located in the side bars 12, near the foot end thereof, are legs 20 to which wheels 21 are secured.

As clearly shown in Fig. 3, the legs 20 comprise upper parts 23 which are secured to the fittings 14 or 19 and lower parts 24 which are secured to the upper parts 23 by means of couplings 25. Bearings 26 of 105 wheel yokes 27 which support the wheels 21 extend into the lower ends of the lower parts 24 of the legs 20. Rods 29 extend upwardly from the bearing portions 26 extending through washers 28 which are 110

clamped between the upper and lower members 24. Lock nuts 31 are placed on the upper ends of the rods 29 for retaining the yokes 27 in place. The lower parts 24, the yokes 27, the washers 28 and the lock nuts 31 are first assembled, being properly adjusted, after which the lower parts 24 are secured to the upper parts 23 of the legs 20.

A fabric 35 is stretched between the side bars 12 and the head and foot bars 13 and 16 of the main frame 11. As shown clearly in Fig. 4, the fabric 35 has side flaps 36 which extend around the side bars 12, a head flap 37 which extends around the head bar 13 and a foot flap 38 which extends around the foot bar 16. The flaps 36, 37 and 38 are provided with eyes 40 through which lacing 41 extends. The lacing is threaded through these eyes of the various flaps in the manner shown in Fig. 4. The lacing is extended around the side bars 12 at 41^a to keep the foot part of the fabric 35 from wrinkling. The manner of lacing shown is very simple and the fabric 35 may be readily removed from the frame 11 when it becomes soiled.

Brackets 45, as clearly shown in Figs. 2 and 3, are secured to the side bars 12 near the head bar 13. Brackets 45 provide lugs 46 around which there extend clevises 47 secured to the lower ends of a head frame 48. As clearly shown in Fig. 1, the head frame 48 is made from a tubular member which is bent into a substantial U-shape as shown. The clevises 47 are secured to the legs 46 by bolts 50 which also extend through hubs 51 of ratchet plates 52, thus serving also to secure these parts of the ratchet plates in place as well as serving as a pivot means for the head frame 48.

The ratchet plates 52 have blocks 54 formed near the upper end thereof, which blocks have channels 55 which engage the head frame 48. U-bolts 56 are provided which extend around the frame 48 and extend through openings in the blocks 54, there being nuts 58 screwed onto the legs of the U-bolt 56 for securing the upper parts of the ratchet plates 52 to the head frame 48. The bolts 50 and the U-bolts 56 rigidly secure the ratchet plates 52 to the head frame 48.

The head frame 48 is provided with a cover in the form of a sack 59 which serves as a fabric for the head structure. This sack 59 is removable and may be readily replaced.

With particular reference to Figs. 2, 3 and 5, pawl ends 61 of a resilient member 62 extend so that they may engage ratchet teeth 63 of the ratchet plates 52. The resilient member 62, as clearly shown in Figs. 2 and 5, is secured to the inside of the head bar 13 by suitable rivets, or bolts, 64. The resilient member 62 has arms 65 which bow, as shown, and which are disposed so

that their widths extend in a vertical plane. The resilient member 62 is twisted at 66 so that the pawl ends have their widths disposed in a horizontal plane. The pawls 61, as clearly shown in Fig. 5, rest on the side bars 12 and are normally in engagement with the ratchet teeth 63. It will be noted in Fig. 3 that upper faces 74 of the ratchet teeth 63 are beveled in such a manner that the ratchet plate may be moved upwardly, but lower faces 75 of the ratchet teeth 63 are made at right angles to the pawls 61 and the ratchets cannot move downwardly unless the pawls are entirely removed from engagement therewith.

A release cord 78 is attached near each end of the arms 65 of the resilient member 62, as clearly shown in Figs. 2 and 3 of the drawings. This pull cord extends through diagonal openings 81 in the head bar 13, as shown in Fig. 3, and connects to a pull cord 79, the upper end of the pull cord being attached to the upper part of the head frame 48 by a suitable clip 80. As previously explained, the ratchet construction will allow the head structure to be moved upwardly, but will prevent it from being moved downwardly unless the pawls 61 are removed from engagement with the ratchet teeth 63. To remove the pawls 61 from this engagement, the pull cord 79 is pulled upon, which pulls the arms 65 of the resilient member 62 rearwardly by means of the pull cords 78, thus moving the pawls 61 rearwardly out of engagement with the teeth 63 and allowing the head structure to be lowered into any desired position. The pawls 61 ride rearwardly on the side bars 12.

Vertical permanent legs 84 and 85 extend up from the corner fixtures 17 (Fig. 1), the leg 84 being slightly longer than the leg 85. The leg 84 is cut away at 86, as shown clearly in Fig. 8. A pin 87 carried in the upper end of the leg 84 extends through a slot 88 formed in a foot frame cross bar 90. The other end of the cross bar 90 has a fixture 91 which attaches a slide leg 92 thereto. When the cross bar is in horizontal position the pin 87 rests in the outer end of the slot 88 and the slide 92 rests in the leg 85. The slide may be retained in the leg by a cotter pin 94 or its equivalent. The foot frame is in this position when the stretcher is being carried and serves as a foot rest for a patient, preventing him from sliding to the foot of the stretcher when carried down stairs. When the stretcher is wheeled, the cross bar is removed into vertical position, as shown in Fig. 7. Such conversion is accomplished by removing the cotter pin 94 and swinging the cross bar into vertical position, as in Fig. 6. The lower end of the cross bar is then telescoped inside the leg 84 as in Fig. 7, this holding it in vertical position. The slide leg 92 provides a con-

venient expedient for pushing and guiding the stretcher.

As shown in Fig. 3, slide bars 95 of a carrying frame 96 extend into the head ends of the side bars 12. The slide bars 95 are connected to a transverse bar 97 by carrying frame fixtures 98. On nipples 99 which may be considered parts of the side bars 12 and which extend outwardly from the fixtures 14 are placed split slide retaining collars 100 which are secured in place by bolts 102. These collars 100 have annular lips 103 which provide openings 104 which are substantially the same size as the slide bars 95. Heads 106 are formed on the inner ends of the slide bars 95, these heads being of a larger size than the openings 104 in the slide collars 100. The carrying frame 96 may be pulled outwardly relative to the main frame 11 until the heads 106 engage the lips 103. When the stretcher is carried, the carrying frame 96 is moved from the position shown in Figs. 2 and 4, into extended position, as shown in Figs. 1 and 3. The transverse bar 97 is then in such a position that it may be readily engaged by an attendant. It is obvious that it would be very inconvenient to grab the head bar 13 because of the head structure. By providing a carrying frame which may be extended, it is very convenient to engage and carry the stretcher. The foot end may be readily lifted by the foot-ends of the side bars 12.

From the foregoing description, it will be seen that my invention provides a stretcher which is very favorable for use in conveying invalids. It is of such a character that it will give a maximum of comfort. The head structure may be adjusted to any position to meet exigencies. The fabrics 35 and 59, as previously described, are readily removable from the frames 11 and 48, and, therefore, when they become soiled may be readily replaced. The adjustable foot frame and the slideable carrying frame provide convenient means for pushing and carrying the stretcher.

I claim as my invention:

1. A stretcher comprising: a wheeled frame lying substantially in a horizontal plane; and a foot frame mounted upon the foot of said wheeled frame, said foot frame including a member normally disposed horizontally and pivoted at one end to swing in-

to substantially vertical position for use as a stretcher guiding post.

2. A stretcher comprising: a wheeled frame having side bars connected by head and foot bars; short posts formed upon said frame at the juncture of said side bars with said foot bar and disposed upwardly therefrom; and a foot rail mounted upon the upper ends of said posts so as to be swingable to form an upward vertical extension upon one of said posts.

3. A stretcher comprising: a wheeled frame having side bars connected by head and foot bars; short hollow posts formed upon said frame at the juncture of said side bars with said foot bar and disposed upwardly therefrom; one of said posts being a pivoting post and having a side opening formed therein connecting with the upper mouth thereof and facing the opposite post; a foot rail having a slot provided longitudinally in an end thereof, said end being adapted to be disposed through said side opening in said pivoting post; and a pin passing through the upper end of said pivoting post and through the slot in said foot rail, so that said foot rail may be pivoted upwardly and slid downwardly into said pivoting post in upright position.

4. A stretcher comprising: a wheeled frame having side bars connected by head and foot bars; short hollow posts formed upon said frame at the juncture of said side bars with said foot bar and disposed upwardly therefrom; one of said posts being a pivoting post and having a side opening formed therein connecting with the upper mouth thereof and facing the opposite post; a foot rail having a slot provided longitudinally in an end thereof, said end being adapted to be disposed through said side opening in said pivoting post; and a pin passing through the upper end of said pivoting post and through the slot in said foot rail, so that said foot rail may be pivoted upwardly and slid downwardly into said pivoting post in upright position; and means for securing the free end of said foot rail to said opposite post when said foot rail is in horizontal position.

In testimony whereof, I have hereunto set my hand at Los Angeles, California, this 1st day of May, 1925.

WILLIAM H. HEISE.
